UNITED STATES PATENT OFFICE.

ROBERT W. GOFF, OF SCHENECTADY, NEW YORK, ASSIGNOR TO GENERAL ELECTRIC COMPANY, A CORPORATION OF NEW YORK.

PUSH-BUTTON SWITCH.

Application filed December 9, 1924. Serial No. 754,851.

My invention relates to improvements in push button switches, and in particular to means whereby the switch may be locked in a desired position.

5 In certain classes of work such, for instance, as in the control of motors for driving printing presses, machine tools and the like, it is customary to provide push button switches for manually effecting a remote 10 control of the driving motors for such equipments. These switches ordinarily comprise a start push button switch and a stop push button switch, the energization of the motor being initially effected through the start 15 push button switch and then maintained through the stop push button switch. There are certain applications for which it is desirable to effect jogging by repeated depression and release of the start push button 20 and in such cases it is necessary to hold the stop push button switch in the open position to prevent the maintaining circuit being established unless some special provision is made therefor. The operator is thus compelled to hold the stop button depressed 25 while he manipulates the start button and this is objectionable.

One of the objects of my invention is to provide a simple, inexpensive and effective 30 arrangement for rendering it unnecessary for the operator to hold the stop push button depressed. Other objects and purposes of the invention will appear in the course of the following description when taken in connection with the accompanying drawing in which I have shown the invention embodied in concrete form for purposes of illustration.

Referring to the drawing, Fig. 1 is a plan 40 view of my improved switch with a portion of the cover for the switch casing broken away in order to show the arrangement whereby the stop push button switch is operated to and held in the open position. 45 Fig. 2 is a sectional view showing the parts of the switch assembly in their respective normal positions. Fig. 3 is a similar cross-section view showing the parts in their respective positions when the stop push button switch is held in its open position. Fig. 4 50 is a perspective view of the various parts of the switch with the casing and the cover of the casing removed for the sake of clearness and Fig. 5 is a very simple diagram of

a motor control system embodying the push 55 button switch of the invention.

Referring to the drawings, the various parts of the switch assembly are mounted within a casing 10 having a cover 11. The various parts of the start and stop push button switches are mounted as a unit on a base 12 of suitable insulating material, the base being secured to the casing 10 in any suitable manner. This push button switch assembly comprises a switch member 13 60 which cooperates with a corresponding contact 14 and forms a normally open starting switch. The push button 15 is provided for operating the switch member 13, the push button 15 projecting from the cover 11 of the 65 casing and being connected with the switch member 13 by means of the post 16. The switch member 17 cooperates with a stationary switch contact 18, the switch member 17 being normally biased into engagement with the contact 18 and forming a normally closed stop switch. The stop push button 19 is connected with the switch member 17 by means of the post 20 and this 70 stop push button likewise projects through the cover of the casing 11. The switch members 13 and 17 are biased so as to be normally in their respective positions as indicated in Fig. 2, by means of the single 75 spring 21 which cooperates with a corresponding end of each switch member. The particular arrangement of a push button switch assembly above described, is the invention of George S. Leddick, for which he obtained Letters Patent of the United States, 80 No. 1,477,884, dated December 18, 1923.

The resilient detent 22 is secured at one end to the cover 11 for the casing of the switch assembly and the free end of this detent is arranged to cooperate with a projection 23 on the stop push button 19. This detent is preferably somewhat resilient and is preferably shaped as shown in the drawing. The operating member 24 for the detent 22 is mounted so as to be carried by the cover 11 by the inherent resiliency of the detent 22; in other words, the operating member 24 is interposed between the detent and the interior surface of the cover 11 and held in that position by the detent. 95 This operating member is provided with a portion 25 which projects from the main body of the operating member through the 100 105

button of the first switch as in normal operation but that the movable member is, under these circumstances, returned from its second to its first position upon the release 5 of this push button.

In accordance with the provisions of the patent statutes, I have described the principle of operation of my invention, together with the apparatus which I now consider 10 to represent the best embodiment thereof, but I desire to have it understood that the apparatus shown is only illustrative and that the invention can be carried out by other means.

15 What I claim as new and desire to secure by Letters Patent of the United States, is—

1. A push button switch having a casing, a movable switch member within the casing, the said switch member being biased to one position, a push button projecting from said casing for operating the switch member to a second position against the bias thereof, a resilient member secured 25 within said casing and arranged to hold said switch member in the second position thereof and normally biased out of cooperative relation therewith, and an operating member for forcing the said resilient member against the bias thereof into holding 30 relation with said switch member, the said operative member being yieldingly held within the casing by said resilient member and having a portion thereof extending 35 from the casing for operating the same.

2. A push button switch having a casing, a movable switch member within the casing, the said switch member being biased to one position, a push button projecting from said casing for operating the switch member to a second position against the bias thereof, a resilient member having one 40 end thereof secured to said casing and the free end thereof arranged to hold said switch member in the said second position thereof and normally biased out of cooperative relation therewith, and an operating member within the casing for forcing the free end of said resilient member against the bias thereof into holding relation with 45 said switch member, the said operating member having a portion thereof projecting from said casing for operating the same.

3. A push button switch having a casing

with a removable cover, a movable switch 55 member mounted within the casing, a push button extending through the said cover and connected with the said switch member, the said switch member being biased to one position and movable by the said push button to a second position, a detent mounted within the said casing and arranged to cooperate with said switch member to move and hold the same in the second position, the said detent being normally biased out 60 of cooperative relation with said switch member, and a reciprocating operating member mounted on said cover within said casing for operating said detent, the said operating member having a portion extending 65 through said cover for reciprocating the operating member to move the said detent into and out of cooperative relation with said switch member.

4. A push button switch having a casing, 75 a movable switch member within the casing, the said switch member being biased to one position, a push button projecting from said casing for operating the switch member to a second position against the bias thereof, a resilient member within said casing having one end thereof held in position and the free end thereof arranged to hold the switch member in its second position and normally biased out of cooperative 80 relation therewith, the said resilient member having a portion angularly disposed to the main body thereof, and an operating member within said casing having a similar angularly disposed portion cooperat- 85 ing with the said resilient member with the angularly disposed portions of said members in alignment when the resilient member is out of cooperative relation with said switch member, the said operating member being yieldingly held within the casing by 90 said resilient member and having a portion thereof extending from the casing for operating the same, whereby moving the said extending portion of the operating member 95 in one direction causes the angularly disposed portion of said member to move the free end of said resilient member into holding 100 relation with said switch member.

In witness whereof, I have hereunto 105 set my hand this 6th day of December, 1924.

ROBERT W. GOFF.
